ATTORNEY

UNITED STATES PATENT OFFICE

170,530

LAVATORY

James M. Hendrickson, Kittanning, Pa., assignor
to Eljer Co., Ford City, Pa., a corporation of
Pennsylvania

Application November 13, 1952, Serial No. 22,272

Term of patent 14 years

(CL. D4—2)

To all whom it may concern:

Be it known that I, James M. Hendrickson, a citizen of the United States, residing at Kittanning, in the county of Armstrong and State of Pennsylvania, have invented a new, original, and ornamental Design for a Lavatory, of which the following is a specification, reference being had to the accompanying drawing forming a part hereof.

Fig. 1 is a top perspective view of a lavatory, showing my new design.

Fig. 2 is a view in perspective from below the lavatory.

I claim:

The ornamental design for a lavatory, as shown.

JAMES M. HENDRICKSON.
